UNITED STATES PATENT OFFICE.

JACOB PFISTER, OF ROCHELLE PARK, NEW JERSEY.

DESIGN FOR A PIPE-CLEANER.

47,144.

Specification for Design.

Patented Mar. 23, 1915.

Application filed December 12, 1914. Serial No. 876,985. Term of patent 14 years.

To all whom it may concern:

Be it known that I, JACOB PFISTER, a citizen of the United States, residing at Rochelle Park, in the county of Bergen and State of New Jersey, have invented a new, original, and ornamental Design for Pipe-Cleaners, of which the following is a specification, reference being had to the accompanying drawing, forming part thereof.

The figure is a plan view of a pipe cleaner, showing my new design.

I claim:

The ornamental design for pipe cleaner, as shown.

JACOB PFISTER.

Witnesses:

ALFRED W. PROCTOR,
L. F. BROWNING.
